[57] CLAIM

The ornamental design for a seat cushion for use in a bathtub or the like, as shown and described.

DESCRIPTION

FIG. 1 is a perspective view taken from the top, front and left side of a seat cushion for use in a bathtub or the like showing our new design;

FIG. 2 is a top plan view thereof;

FIG. 3 is a left side elevational view thereof, the right side elevational view being the mirror image thereof; FIG. 4 is a front elevational view thereof, the rear elevational view being the mirror image thereof;

FIG. 5 is a bottom plan view thereof;

FIG. 6 is a vertical cross-sectional view thereof, taken along line 6—6 of FIG. 2; and

FIG. 7 is a vertical cross-sectional view thereof, taken along line 7—7 of FIG. 2.

FIG. 1

FIG. 2

FIG. 3

FIG. 4
